UNITED STATES PATENT OFFICE.

WILLIAM J. CASEY, OF CHICAGO, ILLINOIS.

DESIGN FOR A SUPPORT OR PEDESTAL FOR LAMPS.

Application filed August 6, 1923. Serial No. 6,953. Term of patent 3½ years.

To all whom it may concern:

Be it known that I, WILLIAM J. CASEY, a citizen of the United States, residing at Chicago, in the county of Cook and State of Illinois, have invented a new, original, and ornamental Design for a Support or Pedestal for Lamps, of which the following is a specification, reference being had to the accompanying drawings, forming part thereof.

Fig. 1 is a side elevation of the new and original design of lamp pedestal.

Fig. 2 is a top plan of the base of the pedestal or support.

I claim:

The ornamental design for a support or pedestal for lamps, as shown.

WILLIAM J. CASEY.
